UNITED STATES PATENT OFFICE.

PAUL A. BREDSVOLD, OF ST. LOUIS, MISSOURI.

LIGHTING-FIXTURE.

1,115,386.

Specification of Letters Patent. Patented Oct. 27, 1914.

Application filed January 2, 1914. Serial No. 809,832.

To all whom it may concern:

Be it known that I, PAUL A. BREDSVOLD, a citizen of the United States of America, residing at the city of St. Louis, State of Missouri, have invented a certain new and useful Lighting-Fixture, of which the following is such a full, clear, and exact description as will enable any one skilled in the art to which it appertains to make and use the same, reference being had to the accompanying drawings, forming part of this specification.

My invention relates to a lighting fixture and consists in various novel features and details of construction, all of which will be described in the annexed specification and pointed out in the appended claims.

In the accompanying drawings, which illustrate one form of fixture made in accordance with my invention, Figure 1 is a side view, partly in section and partly in elevation; Fig. 2 is a top plan view, some of the parts being removed; Fig. 3 is a section on the line 3—3 of Fig. 1, the outer 20 casing being removed; Fig. 4 is a section on the line 4—4 of Fig. 2; and Figs. 5, 6 and 7 are enlarged views showing details of construction.

Like marks of reference refer to similar parts in the several views of the drawings.

10 represents the supporting member which is connected by means of a threaded pipe 11 with a bracket consisting of two parts 12 and 13 respectively, as best shown in Fig. 1. Secured to this bracket by means of screws 14 is a socket 15 of any usual form for supporting an electric lamp bulb 16. The lower part of the bracket 13 is provided with an up-turned portion 17 upon the face 40 of which are formed lugs 18, preferably three in number. Secured to these lugs 18 by means of screws 19 is a reflector 20 of the form best shown in Fig. 5. This reflector 20 has a central opening 21 for the passage of the lamp bulb 16 and said opening is slightly larger than the lamp bulb in order to allow for the passage of heated air between the two members. Arranged within the lugs 18 is a deflector 22 between which 50 and the reflector 20 the heated air is allowed to pass out laterally. In order to prevent the entrance of insects or foreign matter of any kind into this space between the reflector 20 and the deflector 22, I provide an

annular screen 23. The outer edge of the reflector 20 is provided with an upwardly extending flange 24 which is provided with slots 25, preferably three in number, for the passage of pins 26 carried by an annular frame 27. The flange 24 is also preferably provided, adjacent to the slots 25, with recesses 28 into which the pins 26 may rest after the annular member 27 has been slightly rotated. Below the reflector 20 is a second reflector 30 which, like the reflector 20, is provided with a central opening for the passage of the bulb 16, said opening being of sufficient size to allow for the passage of heated air between the bulb and the reflector. The reflector 20 is secured to the reflector 30 by means of a number of plates 31 which also form partitions dividing the reflector into a plurality of compartments, preferably six in number. The partitions 31 may be secured to the reflectors in any suitable manner, but I prefer to provide said partitions with lugs 32 adapted to pass through slots in the reflectors and be bent over, as best shown in Figs. 5 and 6. The annular member 27 is provided with a plurality of openings corresponding in number and size with the compartments formed between the reflectors and each of these openings is adapted to receive a hollow shade 33 of translucent material. Flanges 34 formed on the inner edges of the shades 33 engage with the member 27 so as to hold the shades in position when the annular member 27 is in its normal position. The sides of the shades 33 are made of thicker material than the downwardly and outwardly facing portion 35 thereof, so that more light will be directed downwardly and outwardly than laterally.

36 is a substantially semi-spherical shade 95 of translucent material which is supported from the lower part of the annular member 27 by means of an outwardly projecting flange 37 resting upon the inwardly projecting flange 38 carried by the said member. 100 The lower face of the reflector 30 is adapted to intercept any rays of light which might tend to pass upwardly from the bowl 36, thus preventing the crossing of light rays in the compartments formed by the partitions 31. The bottom of the bowl 36 is provided with an opening for the admission of air and this opening has secured in it a

screen 39 to prevent the entrance of dirt or insects, as best shown in Fig. 1 of the drawings.

The operation of my fixture will be evident. The light from the lamp 16 is directed outwardly by the reflectors 20 and 30 and also by the partitions 31 which also act as reflectors, and is directed in the various hollow protruding shades 33. The lower surface of the reflector 30 also serves to reflect the light downwardly through the bowl 36 and thus prevent the crossing of light rays in the compartments. The heated air which surrounds the bulb 16 may pass up between said bulb and the reflectors 20 and 30 and then pass outwardly between the reflector 20 and the deflector 22. When it is desired to replace the lamp 16, or to clean the parts, it is necessary only to rotate the annular member 27 so that the pins 26 may pass downwardly through the slots 25. In this way, the said member, together with the bowl 36 and shades 33 carried thereby, is removed from the remainder of the fixture. This gives access to the device and thereby allows the parts 33 and 36 to be cleaned as these parts can be entirely removed from the member.

Having fully described my device, what I claim as new and desire to secure by Letters Patent of the United States is:

1. In a lighting fixture, the combination with a source of light, of a support for said light, and a reflector divided into a plurality of compartments, said compartments being arranged side by side in the direction of the circumference of the fixture.

2. In a lighting fixture, the combination with a source of light, of a support for said light, a reflector divided into a plurality of compartments, said compartments being arranged side by side in the direction of the circumference of the fixture, and a plurality of translucent shades coöperating with said reflector.

3. In a lighting fixture, the combination with a source of light, of a support for said light, a reflector divided into a plurality of compartments, said compartments being arranged side by side in the direction of the circumference of the fixture, and a plurality of hollow translucent shades coöperating with said reflector.

4. In a lighting fixture, the combination with a source of light, of a support for said light, a reflector divided into a plurality of compartments, said compartments being arranged side by side in the direction of the circumference of the fixture, and a plurality of hollow protruding shades of translucent material coöperating with said reflectors.

5. In a lighting fixture, the combination with a source of light, of a support for said light, a pair of annular reflectors arranged

one above the other and surrounding said source of light, and partitions between said reflectors and dividing the same into compartments deflecting the light at different angles.

6. In a lighting fixture, the combination with a source of light, of a support for said light, a pair of annular reflectors arranged one above the other and surrounding said source of light, partitions between said reflectors dividing the same into compartments deflecting light at different angles, and a plurality of translucent shades coöperating with said reflectors.

7. In a lighting fixture, the combination with a source of light, of a support for said light, a pair of annular reflectors arranged one above the other and surrounding said source of light, partitions between said reflectors dividing the same into compartments deflecting the light at different angles; and a plurality of hollow translucent shades coöperating with said reflectors.

8. In a lighting fixture, the combination with a source of light, of a pair of horizontal reflectors surrounding said source of light, said reflectors being arranged to allow the passage of heated air between them and the source of light, an outlet for the heated air, said outlet communicating with the space between the reflectors and a foraminous screen protecting said outlet.

9. In a lighting fixture, the combination with a source of light, of a support for said light, a compartment reflector for reflecting the rays from said source in different directions, a plurality of translucent shades coöperating with said reflector, and a translucent bowl arranged below said reflector.

10. In a lighting fixture, the combination with a source of light, of a support for said light, a compartment reflector for directing the rays from said source in different directions, a member detachably carried by said support, and transparent shades carried by said member.

11. In a lighting fixture, the combination with a source of light, of a support for said light, a compartment reflector for directing the rays from said source in different directions, a member detachably carried by said support, and transparent shades detachably carried by said member.

12. In a lighting fixture, the combination with a source of light, of a support for said light, a compartment reflector for directing the rays from said source in different directions, a member detachably carried by said support, translucent shades carried by said member, and a translucent bowl arranged below said reflector and also carried by said member.

13. In a lighting fixture, the combination with a source of light, of a support for said light, a compartment reflector for directing

the rays from said source in different directions, a member detachably carried by said support, translucent shades carried by said member, and a translucent bowl arranged 5 below said reflector and detachably carried by said member.

14. In a lighting fixture, the combination with a source of light, of a support for said light, a compartment reflector for directing the rays from said source in different directions, a member detachably carried by said support, translucent shades carried by said member, a translucent bowl also carried by said member and provided with an air 10 opening and a screen for protecting said air opening.

15. In a lighting fixture, the combination with a source of light, of a support for said light, a pair of annular reflectors surround-

ing said source of light and forming compartments for directing the light at different angles, a member detachably carried by said support, a plurality of translucent shades detachably carried by said member, a translucent bowl also detachably carried by said member, said bowl being provided with an air passage, a screen protecting said air passage, and a second screen arranged above said reflector to permit the passage of the air.

In testimony whereof, I have hereunto set my hand and affixed my seal in the presence of the two subscribing witnesses.

PAUL A. BREDSVOLD. [L.S.]
